UNITED STATES PATENT OFFICE.

WILLIAM L. CALDWELL, OF CHICAGO, ILLINOIS.

COMBINED CALENDAR AND LETTER-BOX.

SPECIFICATION forming part of Letters Patent No. 260,581, dated July 4, 1882.

Application filed January 23, 1882. (Model.)

To all whom it may concern:

Be it known that I, WILLIAM L. CALDWELL, of Chicago, Cook county, Illinois, have invented a new and Improved Combined Calendar and Bill or Letter Box, of which the following is a full, clear, and exact description.

Reference is to be had to the accompanying drawings, forming a part of this specification, in which similar letters of reference indicate corresponding parts in all the figures.

Figure 1 represents a piece of paper or card-board cut, creased, and otherwise suitably prepared to form a combined calendar and bill or letter box in accordance with the invention. Fig. 2 is a partly-broken front view of said box, and Fig. 3 transverse vertical section thereof on the irregular line $\alpha\alpha$ in Fig. 2.

This invention consists in a box constructed to hold within its front and to expose successively through an aperture in its front a series of calendar-cards for the several months and days of the week throughout the year, and having a chamber or space in the rear for bills, letters, or other documents, the whole forming a very useful and convenient appendage for counting-house and business use generally.

The invention also consists in the construction of said box from one sheet or piece of paper or card-board, whereby the same may be produced at such reduced cost as to make it a convenient gift article for advertising purposes.

In Fig. 1 is represented a piece of paper or card-board cut on its one edge, $a\alpha$, to form an ornamental top to the box, and with slits $b\beta$ and c running inward from its opposite edge, and flaps $d\beta$, having hook-shaped extremities $f\beta$. It has also slots or incisions $h\beta$ cut in it for reception of the tongues or hooked portions $f\beta$, and is creased to fold as at $k\beta$, $l\beta$, $m\beta$, $n\beta$, and o . Said piece of paper or card-board likewise has a square or oblong opening, r , cut in it for exposure of the calendar-cards, and parallel strips of wood or other material, $s\beta$, secured to it on its inside face outside of the creases $m\beta$. Thus cut and creased the paper is folded in direction of its creases, the portion a' forming the front of the box, the portions $b'\beta$ an inner divided bottom, the portion $b''\beta$ a full-sized bottom re-enforcing the di-

vided bottom $b'\beta$, the portion c' an outer bottom, the portion d' the back of the box, and the portions $e'\beta$ the sides thereof. After the paper or card-board has been thus folded the flaps d and e are folded over at the back of the box and their tongues or hooked extremities $f\beta$ entered through the incisions $h\beta$ to hold the whole firmly together, as shown in Figs. 2 and 3 of the drawings. Thus constructed or folded, without gum or cement for securing it, the box, which has an open top, is ready for use, the strips $s\beta$ forming a vertical divided space in front for exposure successively through the opening r of a series of removable and reversible or other suitable calendar-cards, $v\beta$, which may be printed to constitute a perpetual calendar, and said box forming in the rear of such card-space a receptacle or space, w , for bills or letters.

Not only is this combined calendar and bill or letter box cheap and easily constructed and secured after the manner of a pocket-book, but the connection of a calendar with a bill or letter box affords the most ready convenience for properly dating the bills or letters received within the box.

The paper or card-board of which the box is made may, if desired, be covered or faced with leather or other suitable material.

Having thus described my invention, I claim as new and desire to secure by Letters Patent—

1. An open-topped box having the division-strips $s\beta$ and hole r , in combination with a series of removable and reversible cards, $v\beta$, whereby a perpetual calendar and bill or letter space are formed, as described.

2. A combined calendar and bill or letter box constructed from a blank of paper or card-board having cuts $b\beta$, c , forming bottom flaps, $b'\beta$, $b''\beta$, and incisions $h\beta$ in it, creased as at $k\beta$, $l\beta$, $m\beta$, $n\beta$, and o , provided with an aperture, r , in its front portion, a' , and with parallel strips $s\beta$ outside of the creases $m\beta$, and formed with flaps $d\beta$, having tongued or hook-shaped extremities $f\beta$, essentially as and for the purposes herein set forth.

WILLIAM L. CALDWELL.
